(57) CLAIM

The ornamental design for a golf divot tool, as shown and described.

DESCRIPTION

FIG. 1 is a perspective view of our golf divot tool in the extended position;

FIG. 2 is a top plan view thereof with the tool in the retracted position;

FIG. 3 is a bottom plan view of the golf divot tool shown in FIG. 2;

FIG. 4 is a right side elevational view thereof;

FIG. 5 is a left side elevation view thereof;

FIG. 6 is a front elevational view thereof; and,

FIG. 7 is a rear elevational view thereof.
